The ornamental design for an architectural structure for a LED light, as shown and described.

DESCRIPTION

FIG. 1 is a left side view of the present invention, FIG. 2 is a right side view of the present invention, FIG. 3 is a top view of the present invention, FIG. 4 is a bottom view of the present invention, FIG. 5 is a front view of the present invention; and, FIG. 6 is back view of the present invention.

The broken lines in the drawings illustrate the environment of the architectural structure for LED light and form no part of the claimed design.
